UNITED STATES PATENT OFFICE.

GEORGE E. PREDOCK, OF ST. LOUIS, MISSOURI, ASSIGNOR TO UDELL-PREDOCK MANUFACTURING COMPANY, OF ST. LOUIS, MISSOURI, A CORPORATION OF MISSOURI.

COMBINATION PLAYER AND PIANO BENCH.

1,049,394.

Specification of Letters Patent.

Patented Jan. 7, 1913.

Application filed January 22, 1912. Serial No. 672,642.

To all whom it may concern:

Be it known that I, GEORGE E. PREDOCK, a citizen of the United States, residing at St. Louis, Missouri, have invented a certain 5 new and useful Improvement in Combination Player and Piano Benches, of which the following is a full, clear, and exact description, such as will enable others skilled in the art to which it appertains to make 10 and use the same.

This invention relates to piano benches.

One object of the invention is to provide a combination piano bench and player piano bench that presents a neat and ornamental 15 appearance and which comprises means for locking the player piano seat to the piano seat of the bench, thus overcoming the necessity of holding the two seats together when music is being removed from or placed 20 in the music compartment of the bench.

Another object is to provide a combination player and piano bench in which the under seat or piano seat is of the same width as the player seat and is designed in 25 such a manner that no corners are formed in which dust and dirt can collect. And still another object is to provide a combined player and piano bench that comprises means of novel construction for hinging 30 the two seats together and for bracing the player seat when it is arranged in a substantially vertical position so as to form a back for the piano seat.

Other objects and desirable features of 35 my invention will be hereinafter pointed out.

Figure 1 of the drawings is a perspective view of a combination player and piano bench constructed in accordance with my 40 invention; Fig. 2 is a similar view showing the player seat arranged in vertical position so as to form a back for the piano seat; Fig. 3 is a perspective view illustrating both 45 seats of the bench raised so as to obtain access to the music compartment; Figs. 4, 5 and 6 are end views of Figs. 1, 2 and 3, respectively; Fig. 7 is an enlarged vertical 50 sectional view taken on approximately the line 7—7 of Fig. 4 illustrating the construction of the means that is used for detachably connecting the two seats together; Fig. 8 is a detail view taken at approximately 55 right angles to Fig. 7; Fig. 9 is an enlarged vertical sectional view taken on approximately the line 9—9 of Fig. 4; and Fig. 10

is a transverse sectional view taken through the seats of the bench illustrating one of the brackets to which the player seat is connected.

Referring to the drawings which illustrate the preferred form of my invention, A designates the music compartment of the bench which is preferably made wide enough to receive rolls of music α such as are used in player pianos; B designates the 60 piano seat or under seat of the bench which forms a cover for the music compartment, and C designates the player piano seat which is arranged above the piano seat B so as to form a comparatively high bench 65 70 such as it is preferable to use when operating a player piano, the player seat C being mounted in such a manner that it can be moved into an approximately vertical position, as shown in Figs. 2 and 5, so as to 75 form a back for the piano seat B when the bench is being used by a person playing a piano. The piano seat B extends the entire length of the bench and is approximately the same width and length as the player seat 80 C, thus producing a bench that can be kept clean easily because no side pieces are used at the ends of the piano seat. In other words, the top face of the piano seat is smooth and free from corners in which dust 85 and dirt can collect and consequently the dust can be removed from said seat easily by simply rubbing a cloth over same.

The piano seat B is connected to the music compartment of the bench preferably 90 by means of hinges 1 that are fastened to the under side of the piano seat B and to the upper edge of the rear wall of the music compartment A, as shown in Fig. 3. The player seat C is hinged at its rear edge 95 to the piano seat B, and means is provided for detachably connecting said seats together so as to overcome the necessity of manually holding the player seat C to prevent it from dropping rearwardly when the 100 piano seat B is raised to obtain access to the music compartment, as shown in Figs. 3 and 6. In the preferred form of my invention, as herein shown, a pair of brackets 2 are secured to the top face of the piano seat B 105 adjacent the rear edge of same, and members 3, which are connected to the under side of the player seat C, are pivotally connected to the upper ends of the brackets 2 by means of pintles 4. The members 3 are 110

preferably formed from pressed metal and are substantially U-shaped in cross section, and at the rear ends of said members 3 the horizontal webs of same are cut away so that the upper ends of the brackets 2 will lie between the side legs or flanges of the members 3, thus producing a strong hinge connection between the two seats B and C and overcoming any tendency of the player seat to move longitudinally relatively to the piano seat. The members 3 preferably extend approximately the entire width of the player seat C so as to reinforce and strengthen same, and devices are fastened 15 to the front ends of the members 3 so as to coöperate with devices on the piano seat for detachably connecting said two seats together. Various kinds of devices can be used for locking the player seat to the piano seat but I prefer to provide the player seat with depending arms 5 having substantially ball-shaped ends 5^a that are adapted to coöperate with spring sockets 6 arranged in recesses 6^a that are formed in the top face 20 of the piano seat B, as shown in Figs. 7 and 8, the upper ends of the arms 5 projecting through slots in the webs of the U-shaped members 3 and being rigidly secured to said member by rivets 7.

30 When the player seat is lowered from its vertical position into its horizontal position, as shown in Fig. 1, the ball-shaped ends of the arms 5 on the player seat enter the spring socket 6 in the piano seat and thus 35 securely lock the seats B and C together so that the player seat will not fall backwardly away from the piano seat when the piano seat is raised as shown in Figs. 3 and 6. While the devices 5 and 6 just referred to operate to lock the seats B and C together, it will, of course, be understood 40 that the player seat C can be released easily whenever the operator desires to raise same into its vertical position, owing to the fact that the ball-shaped sockets 6 in the piano seat only exert yielding pressure on the ball-shaped ends of the devices 5 on the player seat. The rear edges of the brackets 2 are inclined rearwardly slightly, as shown in 45 Fig. 10, and the player seat C is connected to said brackets in such a manner that the lower edge portion of said player seat will bear against the rear edges of the brackets 2 when the player seat is raised or 50 arranged in an approximately vertical position as shown in full lines in Fig. 5 and in broken lines in Fig. 10, the brackets 2 thus operating to brace the back rest of the piano seat and hold said back 55 rest in a slightly inclined position so that there will be no tendency for it to swing downwardly back to its horizontal position.

60 A bench of the construction above described can be used by a pianist or by a person 65 operating a player piano because it com-

prises two seats, one located at the most convenient height for playing a piano, and the other located at the most convenient height for operating a player piano.

The bench has a large compartment that 70 can be used for storing sheet music or rolls of music such as are used in player pianos, and when the piano seat is in use the player seat acts as a back rest. The two seats are detachably connected together in such a 75 manner that it is not necessary to manually hold the player seat when the piano seat is raised to obtain access to the music compartment, and the means used for hinging the seats together is so designed that the player seat is braced securely when it is arranged 80 in a vertical position, and is so mounted that there is no tendency for it to move longitudinally relatively to the piano seat.

In addition to the desirable features 85 above-mentioned my improved bench presents a neat and ornamental appearance and it is so designed that it can be kept clean easily.

Having thus described my invention, what 90 I claim as new and desire to secure by Letters Patent is:

1. A combination player and piano bench provided with a piano seat, a player seat arranged in a higher horizontal plane than 95 said piano seat, upwardly projecting brackets on the top face of the piano seat whose rear edges are inclined rearwardly, and means for hinging the player seat to said brackets in such a manner that the lower 100 edge portion of said seat will bear against the rear edges of said brackets and thus be braced and supported in an inclined position by same when the player seat is raised.

2. A combination player and piano bench 105 provided with a music compartment, a hinged top for said compartment that forms a piano seat, a player seat arranged above said piano seat, upwardly projecting brackets on the top face of said piano seat set inwardly some distance from the rear edge of 110 said seat and having inclined rear edges, transversely extending members on the under side of the player seat that embrace the upper ends of said brackets, and pintle pins 115 passing through said members and brackets for pivotally connecting them together, said pintle pins being so arranged that the brackets will brace the player seat and hold it in an inclined position when said seat is 120 raised.

3. A combination player and piano bench provided with a music compartment, a hinged piano seat that forms a cover for 125 said compartment, a player seat arranged in a higher horizontal plane than said piano seat, upwardly projecting brackets on the top face of the piano seat set some distance inwardly from the rear edge of same, transversely arranged metallic members on the 130

under side of the player seat that are substantially U-shaped in cross section, said members being slotted so as to receive the upper ends of said brackets, pintles passing through said brackets and members, rigid depending arms on the under side of the player seat that project through slots in the webs of said U-shaped members and are connected thereto so as to support the front edge of the player seat, said arms having ball-shaped ends, and spring sockets set in

recesses in the top face of said piano seat for receiving the ball-shaped ends of said arms.

In testimony whereof I hereunto affix my signature in the presence of two witnesses, this sixteenth day of January 1912.

GEORGE E. PREDOCK.
